UNITED STATES PATENT OFFICE.

WILLIAM C. GARDNER, OF ALTOONA, PENNSYLVANIA.

TRACK-SANDER.

SPECIFICATION forming part of Letters Patent No. 708,473, dated September 2, 1902.

Application filed April 22, 1902. Serial No. 104,201. (No model.)

To all whom it may concern:

Be it known that I, WILLIAM C. GARDNER, a citizen of the United States, residing at Altoona, in the county of Blair and State of Pennsylvania, have invented new and useful Improvements in Track-Sanders, of which the following is a specification.

This invention relates to track-sanders; and the primary object thereof is to produce a delivering device adapted to be secured to an engine at a convenient point to receive sand from the sand-box and from which the sand is discharged upon the tracks by means of compressed air from the air reservoir or exhaust.

Another object of the invention is to produce a sand-deliverer in which the sand is kept perfectly dry, whereby all liability of the same becoming caked and rendering the device inoperative is obviated.

The invention consists in the construction, combination, and arrangement of parts hereinafter fully described and claimed.

In the drawings, Figure 1 is a central longitudinal sectional view of a delivering device constructed in accordance with my invention. Fig. 2 is a central transverse sectional view thereof. Fig. 3 is a central horizontal sectional view of the same.

1 designates a rectangular chamber adapted to be secured upon the engine at a convenient point to receive sand from the sand-box and to discharge the sand upon the tracks. The chamber is provided with a threaded inlet 2 and two threaded outlets 3. The inlet 2 receives the threaded end of a pipe 4, suitably connected to the sand-box of an engine to convey sand therefrom to the chamber. The outlets 3 receive the threaded ends of pipes 5, having their opposite free ends arranged adjacent the tracks to deposit sand thereon. The chamber is provided with a removable plug 6 in the bottom thereof to permit the sand to be removed therefrom when found advantageous to clean or repair the chamber.

A partition 7 is arranged within the casing and provided with passages 8, having opposite discharge-openings 9, carrying jet-nozzles 10. Communicating with the beginning

of the passages are threaded inlet-openings 11, adapted to receive the threaded ends of air-pipes 12, suitably connected with the

compressed-air reservoir or the exhaust to convey air therefrom to the passages 8, discharging sand upon the tracks in a manner 55 as is obvious. The pipes 12 are provided with valves to be controlled by the engineer to permit the regulation of the amount of sand to be discharged upon the tracks.

It will be perceived that when sand is let 60 into the chamber 1 and when the compressed air is permitted to pass through the passages 8 the sand is forced through the pipes 5 in jets to be deposited upon the track through the medium of jet-nozzles 10, which reduces 65 the stream of air to a jet.

The chamber 1 has the sides and edges thereof provided with communicating steam-pockets 13, and one side thereof is provided with a threaded inlet 14, adapted to receive 70 the threaded end of a pipe 15, having its opposite end suitably connected to the steam-chest or the exhaust to supply pockets with steam. The pipe 15 has arranged intermediate its ends to be within easy reach of the 75 engineer to enable him to control the supply of steam in the pockets 13 a valve. A steam-exhaust 16 is arranged on the chamber upon the opposite side to that of the inlet 14 and at an extreme point near the lower end thereof to insure against all liability of condensation remaining in the pockets. The exhaust is of a diameter much smaller than the inlet, whereby the exhaust of steam is much slower than the feeding thereof, whereby the pockets 80 are at all times sufficiently supplied with steam. The exhaust of the steam, although it be slower than the feeding thereof, will not permit the condensation of the steam in the pockets to any great extent. 85

It will be perceived that by surrounding the chamber with steam-pockets the sand contained therein will be kept dry at all times, thereby obviating any liability of the sand becoming clogged, and consequently 95 rendering the device inoperative.

The operation of the device will be clearly understood from the above description, taken in connection with the accompanying drawings, and therefore a further description is 100 deemed unnecessary.

It will be obvious from the description and drawings that I provide a device which will effectually prevent the sand from becoming

clogged from moisture and by means of which sand may be deposited upon the tracks and which is cheap, durable, and efficient.

Having thus fully described the invention, 5 what is claimed as new is—

1. A track-sander, comprising a sand-receiving chamber surrounded by a steam-pocket, and a sand-discharging device arranged within the chamber.
- 10 2. A track-sander, comprising a sand-receiving chamber surrounded by a steam-pocket, a sand-discharging device arranged within the chamber, and jet-nozzles carried by the discharge device.
- 15 3. A track-sander, comprising a sand-receiving chamber surrounded by a steam-pocket, said chamber being provided with outlets, a sand-discharging device arranged within the chamber, and provided with discharge-openings alined with the outlets, and jet-nozzles carried by the discharge-openings.
- 20 4. A track-sander, comprising a chamber surrounded by a steam-pocket, means for feeding sand thereto, a partition arranged within the chamber and provided with pas-

30 sages having opposite discharge-openings, jet-nozzles arranged in the discharge-openings, means for feeding steam to the passages to discharge the sand, means for supplying steam to the pockets, and an exhaust adapted to control the supply of steam in the pockets.

5. A track-sander, comprising a sand-receiving chamber surrounded by a steam-pocket, and a sand-discharging device arranged within the chamber, and formed integral therewith.

35 6. A track-sander, comprising a sand-receiving chamber surrounded by a steam-pocket, and provided with outlets, a partition within the chamber and formed integral therewith, said partition being provided with 40 passages having oppositely-located inlet and discharge openings.

In testimony whereof I affix my signature in presence of two witnesses.

WILLIAM C. GARDNER.
